UNITED STATES PATENT OFFICE

2,602,311

TRAY ATTACHMENT

Roy Dahl Hansen, Alameda, Calif.

Application December 18, 1946, Serial No. 717,019

1 Claim. (Cl. 65—65)

1

This invention relates to trays, and more particularly to novel improvements in serving trays and is in the nature of a continuation in part of my copending application for United States Letters Patent Serial No. 656,451, filed March 22, 1946.

The principal object of the present invention is to provide a novel serving tray with removable attachments to hold and restrain from unwanted movement various types of drinking glasses or the like. A particular object of the invention is to provide a tray of the above mentioned type with clip members which, when engaged with the tray, will provide a means to grip removably a stem-type glass or a tumbler-type glass and allow their convenient removal and redeposit. A further object is to provide a tray of the above mentioned type with recesses to hold and restrain from unwanted movement drinking glasses of various types. A further particular object is to provide a tray of the above mentioned type, having a clip member so designed that when placed in one position a stem-type glass will be accommodated, and when positioned invertedly a tumbler-type glass will be accommodated. A further object is to provide a tray, whereon an attachment therefor, adapted to engage and hold a glass thereon, acts as a balancing element to prevent tilting of said tray.

Other objects and advantages will become apparent upon reference to the accompanying specification and drawings. In the drawings similar characters of reference represent corresponding parts in the several views.

Fig. 1 is a top plan view of a tray embodying the invention.

Fig. 2 is a sectional view, taken on line 2—2 of Fig. 1.

Fig. 3 is a top plan view of a modification of the tray.

Fig. 4 is a sectional view, taken on line 4—4 of Fig. 3.

Fig. 5 is a top plan view of a further modification of the attachment.

Fig. 6 is a top plan view of a further modification of the attachment.

Fig. 7 is a sectional view, taken on line 7—7 of Fig. 5.

Fig. 8 is a sectional view taken on line 8—8 of Fig. 6.

The invention is herein illustrated in Fig. 1 with an individual serving tray, generally indicated at A, provided with an hors d'œuvre, food or ash containing recess at 3, and a glass supporting portion at 4. The tray is formed with

outward horizontally projecting side edges 5. The tray may be formed from a metal or plastic blank by means of stamping or the like. A clip member, generally indicated at 6, is formed of a preferably resilient material, such as sheet aluminum or the like, and comprises glass engaging finger members 7, which overlie the glass supporting portion of the tray 4, and a U-shaped clamp portion 8 to grip, removably an edge 5 of the tray A.

Fig. 2 illustrates the clip 6 positioned on the tray A. The foot of a stem-type glass 9 is held, removably, to the glass supporting portion 4 of the tray A by the resilient members 7 of the clip 6. The under part of the clamp portion 8 is bent back upon itself, as at 10, the same depth as the bottom of recess 3 to form a balancing and supporting element for the tray. The clip 6 may be slidably disengaged from the tray A so that the tray may be used without the clip, if so desired.

Fig. 3 illustrates a modification of the invention, wherein a glass containing depression 11 is stamped into the tray B the same depth as recess 3^a, the depression 11 having side walls to restrain glasses of various types from undesired movement. A supporting or balancing element for the tray is provided by a depression, indicated at 12, which is formed so that the bottom thereof lies the same horizontal plane as the bottom of depressions 11 and 3^a. A clip 6^a engages edge 5^a and the resilient fingers 7^a thereof overlie the glass supporting portion 4^a and depression 12 and grip, removably, the base of a stem-type glass 9 placed therein, as illustrated in Fig. 4.

Fig. 4 illustrates a cross section of the tray shown in Fig. 3 with depressions 11 and 12. Depression 11 supports tumbler-type glasses 13 of various types and depression 12 serves as a balancing and supporting member for the tray.

Figs. 6 and 8 illustrate a further modification of the invention, wherein tray A is identical to that described above with reference to Figs. 1 and 2 and wherein a tumbler-type glass retaining clip member, generally indicated at 15, is clamped to the edge 5 of the said tray by a U-shaped clamp portion 16. The member 15 comprises an annular flange 17 which overlies the glass supporting portion 4 to hold and restrain from unwanted movement a tumbler-type glass 13. The clamp portion 16 is bent back upon itself, as at 18, similarly to clamp portion 8 heretofore described.

Figs. 5 and 7 illustrate another and preferred modification of the present invention and where-

in the same tray described with reference to Figs. 1, 2, 6 and 8 is utilized. A glass holding member is indicated generally at 21 and comprises a clip portion 22, which is substantially identical with the clip member 6 described with reference to Figs. 1, 2, 3, 4 and 5 and is adapted to clamp a stem-type glass to the glass holding portion 4 of tray A by means of resilient diverging fingers and a ring member 23 which is the same as that described with reference to Figs. 6 and 8. The ring member 23 and clip member 22 are joined together by a U-clamp 24 which is preferably formed integrally with said clip and said ring member and the clamp 24 is adapted to engage slidably the tray edge 5, as indicated in Fig. 7. The clip 22 is bowed outwardly, as at 25, so that when the said clip portion is positioned below the glass supporting portion 4 the bowed portion lies in the same horizontal plane as the bottom of recess 3 of tray A. Similarly, the ring member 23 is formed so that when it occupies the underside of the glass supporting portion 4 it acts as a balancing element for the tray, as illustrated in Fig. 7.

The novel glass holding member will accommodate stem-type glasses when used in the position illustrated in Fig. 7 and will accommodate tumbler-type glasses when the member is removed from the tray and re-attached thereto so that the ring member overlies the glass holding portion. Hence I have described a unitary clip member adapted to hold glasses of various types by the simple expedient of reversing the position of the glass retaining member relative to the glass supporting portion of the tray. Obviously a tray may be designed by those skilled in the art which itself may be reversed without the necessity of reversal of the glass engaging and retaining member in order to accommodate various types of glassware.

While the invention has been described in more or less specific detail for purposes of clarity of description, it is understood that modifications and variations in detail of the structure may be accomplished within the scope of the appended claim.

I claim:

A glass holding clip for attachment to a tray having a depressed portion and a marginal hori-

zontally projecting edge disposed above the bottom of the depressed portion of the tray, said clip comprising a flat strip of resilient material formed at one end to provide a pair of laterally spaced fingers arranged to overlie the top of said tray edge and formed to clamp the foot of a stem glass against said top of said tray edge and formed to receive the stem of a glass therebetween and to clamp the foot of said glass against said top of said tray edge, a clamp integral with said pair of fingers arranged to grip removably said edge, and means comprising a projection arranged to underlie said edge and integral with said clamp to afford support to said tray to prevent tilting thereof when a glass is placed on the edge of said tray, the bottom of said projection lying in substantially the same plane as the bottom of said depressed portion.

ROY DAHL HANSEN.
